UNITED STATES PATENT OFFICE.

ELMER E. WILLIS, OF MINETTO, NEW YORK, ASSIGNOR OF ONE-HALF TO ALPH ST. AMONT, OF MINETTO, NEW YORK.

CONCRETE-MIXER.

1,074,918.

Specification of Letters Patent.

Patented Oct. 7, 1913.

Application filed September 27, 1912. Serial No. 722,730.

To all whom it may concern:

Be it known that I, ELMER E. WILLIS, a citizen of the United States, residing at Minetto, in the county of Oswego and State 5 of New York, have invented a new and useful Concrete-Mixer, of which the following is a specification.

This invention relates to an improvement in concrete mixers.

10 The primary object of the present invention is to provide a machine of this character which will accurately supply sand and cement in predetermined quantities to a mixing mechanism.

15 A further object of the invention is to provide simple and efficient means for closing the sand and cement hoppers, while the troughs which receive the material from said hoppers are dumping.

20 A still further object of the invention is to provide means for locking the dumping troughs together, in order that the same may dump consonantly.

25 A still further object of the invention is to provide an accurate weighing mechanism which may be readily and conveniently adjusted when it is desired to vary the quantity of sand and cement supplied to the mixing mechanism.

30 A still further object of the invention is to provide an efficient mixing mechanism which will thoroughly mix the sand and cement, spraying the same with water as it is being mixed.

35 In the drawings Figure 1 is a side elevation of the machine. Fig. 2 is a vertical section. Fig. 3 is a vertical transverse section. Fig. 4 is a section taken on line 4—4 of Fig. 1 looking downwardly. Fig. 5 is 40 a detail view of the trough which receives the commingled sand and cement, and Fig. 6 a detail view of the latch mechanism which holds the sand trough against dumping until the cement trough has received 45 a predetermined quantity of cement.

In the drawings, 10 designates the supporting frame, which consists of the vertically extending angle beams 11, 12, 14 and 15 which are connected at their upper ends 50 by the longitudinally disposed angle beams 16 and 17, each set of vertical beams being connected by the transversely extending beams 18 and 19 which are also of angle iron. The longitudinal beams 16 and 17 support a plurality of hoppers 20 and 21,

these hoppers being preferably formed of sheet metal, bent to embrace the angle beams 16 and 17, and the transverse beams 18 and 19, the transverse beam 24 connecting the beams 16 and 17 intermediate their ends, the 60 hoppers having the overlapping portions 25, which embrace the transverse beams 24. The second set of longitudinal beams connect the vertical standards intermediate their ends, this second set of beams supporting a plurality of pivoted troughs which receive material from the hoppers 20 and 21. The vertically extending beams, being connected by braces 26 which are V-shaped and are secured to the second set of beams 65 intermediate their ends. The vertically extending beams are also connected by a second set of transverse beams 27 and 28 which are inwardly disposed to support the second set of longitudinal beams 29 which are 70 also disposed inwardly, the transverse beams 27 and 28 also supporting another set of longitudinal beams which are disposed outwardly, their edge portions 29' lying flush with the edge portions of the longitudinal 75 beams 31, thus forming a frame consisting of longitudinally disposed U-shaped members, which form a support for a plurality of pivoted troughs which receive the material from the hoppers 20 and 21 and to 80 which the mixing mechanism is secured.

The mixing mechanism consists of the hopper 33, the extensions 34 of which are secured to brackets 35 which overhang the inner angle beams, said hangers and the extensions of the hoppers extending inwardly and upwardly to support the pivoted troughs at a point immediately below the openings in the hoppers 20 and 21. The openings in these hoppers are closed by adjustable slides 35' which are adapted to restrict or entirely close said openings. Each of the hoppers is provided with a pivotally supported closure which consists of a plate 37, having the off-set portions 38, each of which portions 38, is pivotally connected to two hangers 39. The hangers 39 are pivotally connected to brackets 40 supported by the longitudinal beams 16 and 17, these pivoted arms 39 being arranged on either side 90 of the same, the plurality of arms being adjustably connected to each of the off-set edges of the plates 37. It will be noted by this construction that the plates 37, normally swing beneath the openings in the 95 100 105 110

hoppers, preventing the material contained therein from falling within the pivoted troughs which deposit the same in the mixing device. The plate which is disposed beneath the cement hopper 20 is provided on its under face with a substantially U-shaped member 41 which straddles the rear wall 42 of one of the pivotally supported troughs 43 arranged beneath the cement hopper. Thus it will be seen that movement imparted to the trough will force the plate 37, beneath the hopper 20, preventing the material contained therein from falling, while the trough 43 is dumping. The trough is normally held parallel with the longitudinal beams by a weight 44 which is arranged on the bar 45 secured to the trough, the trough being pivotally supported between the brackets 35. It will be noted by this construction that the hoppers 20 is provided with a plurality of closures, the adjustable slide 35' which is manipulated by means of pivotally connected levers 48 and 49 supported by a bracket 50 secured to the hopper 20. The hopper 21 which is adapted to contain the sand is of practically the same construction as the hopper 20, the same, however, being provided with a brush 51. The plate 51' forms the closure for the hopper 21 and prevents the sand from falling while the trough 43 which is arranged below the sand hopper, is dumping. This trough is also provided with a weighted bar 52 which is connected by means of a chain 53 to a bell-crank 54 pivotally supported by a bracket 55' secured to the transverse beam 19. The other end of said bell crank having a link connection with the plate 51', which when the trough 43 is dumped, allows the plate due to the weight of the plate 51' and the tendency of the hangers 39 to assume a vertical position, to close the hopper, the normal tendency of the plate being to close said hopper, the same being held open by the trough, when the same is in its receiving position.

In order to accurately regulate the quantities which the troughs 43 are to receive a beam 55 is pivotally supported by a bracket 56 at a point adjacent the meeting ends of the troughs, said beam being provided with a latch member 57 which permits the free upward movement of the trough arranged beneath the cement hopper, which is adapted to contact with the off-set end 59 of the bar 60 which is secured to said trough preventing the same from moving downward. Arranged on the bar 55 is a weight 61, which may be adjusted to determine the amount of material necessary to tip the bar. Thus it will be noted that the amount of material which will be deposited within the cement hopper may be accurately regulated by an adjustment of the weight 61. In order that the troughs 43 may deposit the ma-

terial consonantly, the latch member 62 is provided which consists of a pivotally supported latch bar 67 supported by the bracket 68 and being guided in its movement by the bifurcated standard 69. Arranged on the end of said pivoted bar is a pivoted latch member 70 which while restricting the downward movement of the cement trough, allows the same to assume its position after dumping. The latch bar is provided with a notch, and said bar lies in the path of a projection 72 carried by the sand trough, said bar normally preventing said trough from dumping. It will be noted however, that as the cement trough is filled and dumped, the bar 67 will be tipped, which will release the sand trough, the two troughs dumping consonantly.

The material which is dumped is deposited within the hopper 33 which terminates in the spout 74. To this hopper is secured the mixing chamber 75. Arranged within said chamber immediately below the spout of the hopper 33 and on which the material falls is a V-shaped deflector 77 which is disposed longitudinally of the chamber 68. Arranged below said deflector are the pivotally supported troughs 79 and 80 shown in detail in Fig. 6. These troughs are hingedly connected to the side walls of the casing, and are connected with the latch member 83 which permits the members to swing freely on their pivots. This latch member consists of the arm 84 which extends through an eye 85 carried by the other trough, the arm being curved and provided with an enlarged head which prevents the same from leaving the eye. Both of the troughs are provided with curved stops 86 which limit their downward movement, said stops 86 contacting with the side walls of the casing. The troughs are held against dumping by the weight 87 secured to the arm 88 which projects through the casing and which is secured to one of the troughs. The other trough is provided with a similar arm 89 which operates the valve 90 through the link 91, said valve being opened as the trough dumps, allowing the water to flow through the pipe 92 and be sprayed through the material by the rectangular nozzle 93.

In operation the material is supplied to the hoppers 20 and 21 and the same supplied by the hingedly supported trough, to the mixing mechanism. The material passes through the hopper 33 becoming mixed during its descent and is further mixed as the same falls upon the V-shaped deflector arranged immediately below the distributing end of the hopper 33. It then falls upon the trough 82 and when sufficient of the material has fallen on said trough the same dumps and deposits the same on the conical deflector 92 which is disposed immediately below the trough 82, the same being sprayed

by the nozzle 93 as it passes over the deflector. This manner of handling the material in the mixing chamber assures a perfect mixing of the material, as the same is not dumped in one mass through a series of agitators but is deposited in small quantities, being mixed as it is handled each time, the trough 82, depositing the same periodically on the conical deflector in the same manner 10 that the trough 43 deposits the same within the main hopper 33.

The many advantages of a mixing and weighing mechanism of this character will be clearly apparent as it will be noted that 15 the material is effectually mixed in a simple and convenient manner and that the entire structure is such as may be cheaply and economically constructed, the entire operation of the feeding and mixing being automatic 20 as long as the hoppers 21, and 20 receive material. Attention is also called to the mechanism by means of which the quantity which is periodically supplied to the mixing chamber may be accurately regulated, and 25 means for closing the main supply hoppers while the material is being supplied to the mixing mechanism, thus positively preventing a continued flow of the material from the supply hoppers, the material as before 30 stated being passed through the mixing mechanism in small quantities which assure an even and proper mixture.

What is claimed is:—

1. In a concrete mixing and weighing machine, a frame, a plurality of hoppers supported by said frame, a plurality of plates arranged to form closures for the delivery openings in said hoppers, arms supporting said plates, said arms being pivotally supported by said frame, a trough arranged beneath said hoppers, a U-shaped member carried by one of said plates, said member straddling the rear wall of one of said hoppers, a bell crank supported by said frame, a 45 chain connecting said bell crank with the other of said troughs, and a link connection

between said bell crank and one of said plates.

2. In a concrete mixing and weighing machine, a plurality of stationary hoppers, a plurality of pivoted troughs arranged beneath said hoppers, a receiving hopper arranged below said troughs, a second set of pivoted troughs arranged below the receiving hopper, said troughs having a connection whereby the same will dump consonantly. 55

3. In a concrete mixing and weighing machine, a plurality of hoppers, a plurality of stationary troughs arranged to receive material from said hoppers and means actuated by said troughs for closing the delivery openings in said hoppers, a receiving hopper arranged below said troughs, a deflector arranged beneath said receiving hopper and a plurality of pivoted troughs arranged below 60 said deflector, said troughs dumping consonantly. 65

4. In a concrete weighing and mixing machine, a plurality of stationary hoppers, a receiving hopper, means for delivering the material to said receiving hopper in predetermined quantities, said means including troughs arranged to dump consonantly and a plurality of troughs receiving the material 75 from said receiving hopper. 70

5. In a concrete mixing and weighing machine, a plurality of stationary hoppers, a plurality of troughs arranged beneath said hoppers, a receiving hopper, a plurality of 80 weighted troughs arranged beneath said receiving hopper, said troughs being provided with stops adapted to limit their downward movement.

In testimony that I claim the foregoing as 85 my own, I have hereto affixed my signature in the presence of two witnesses.

ELMER E. WILLIS.
